US00D939370S

(12) **United States Design Patent** (10) **Patent No.:** **US D939,370 S**
(45) **Date of Patent:** **** Dec. 28, 2021**

(54) **BODY FAT WEIGHT SCALE**

(71) Applicant: **ETEKCITY CORPORATION**,
Anaheim, CA (US)

(72) Inventors: **Lin Yang**, Shenzhen (CN); **Hai Yang**,
Shenzhen (CN)

(**) Term: **15 Years**

(21) Appl. No.: **29/717,505**

(22) Filed: **Dec. 18, 2019**

(30) **Foreign Application Priority Data**

Jun. 18, 2019 (CN) 201930316076.9

(51) **LOC (13) Cl.** **10-04**

(52) **U.S. Cl.**

(57) **CLAIM**

The ornamental design for a body fat weight scale, as shown and described.

DESCRIPTION

FIG. 1 is a perspective view of a body fat weight scale showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof showing in an alternative in-use configuration.

(Continued)

The broken lines depict portions of the body fat weight scale that form no part of the claimed design.

1 Claim, 8 Drawing Sheets
